[57] CLAIM

The ornamental design for a contactor, as shown and described.

DESCRIPTION

FIG. 1 is a top, front, and right side perspective view of a contactor showing my new design;

FIG. 2 is an enlarged front perspective view thereof;

FIG. 3 is an enlarged left side elevational view thereof, the right side being a mirror image of that shown; and FIG. 4 is an enlarged top perspective view thereof, the bottom being a mirror image of that shown except for that portion visible in FIG. 1, and the rear being plain and unornamented.

FIG. 1

FIG. 2

FIG. 3

FIG. 4
